PREHEATER

Nathan A. Arvins and Abraham A. Arvintz,
Brooklyn, N. Y., assignors to Blazel Corporation,
a corporation of New York

Application November 11, 1944, Serial No. 563,028

3 Claims. (Cl. 257—240)

1

This invention relates to preheaters primarily used for preheating fuel oil for supply to oil burners of various kinds and classes. More particularly, the invention relates to apparatus of this kind having yieldable means compensating for expansion and contraction of the circulating unit and the casing or jacket therefor, in order to prevent stresses or strains on the unit. Further, the invention includes the use of a coil, through which the heating medium is circulated and the arrangement of this coil in the jacket or casing of the apparatus to heat a transfer medium contained therein for heating the circulating coils of said unit. Still further, the invention includes means for circulating the medium in the casing or jacket to provide more efficient heat conductivity and to eliminate dead pockets in the apparatus.

Some features shown and described herein are claimed in our divisional application No. 726,420, filed February 4, 1947.

The novel features of the invention will be best understood from the following description when taken together with the accompanying drawing, in which certain embodiments of the invention are disclosed and in which the separate parts are designated by suitable reference characters in each of the views and in which:

Fig. 1 is a longitudinal sectional view through an apparatus made according to our invention with the central portion of the apparatus broken away.

Fig. 2 is a section on the line 2—2 of Fig. 1 on a reduced scale.

Fig. 3 is a section on the line 3—3 of Fig. 1 on a reduced scale; and

Fig. 4 is a sectional view at right angles to Fig. 1 showing one end portion only of the preheater.

In the accompanying drawing, 10 represent the main casing or jacket of the preheater apparatus. The ends of the casing have outwardly projecting annular flanges 11 and 12. The end portions of the casing, adjacent the flanges, have ports 13, 14, 15 and 16 which, in the construction shown, are closed by plugs 17, 18, 19 and 20. However, in some instances, these ports may be used to circulate a heating or transfer medium through a chamber 21 of the casing 10.

At one end of the casing 10 and detachable with respect to the flange 12 is an oil distributing casing or header 22 having an annular flange 23 secured to the flange 12 by circumferentially spaced bolts 24. An oil inlet pipe 25 is coupled with the header 22 and communicates with a

2

passage 26 in the header. The header also has an oil outlet passage 27 which communicates with another passage 28 in the header. Between the passages 26 and 28 is a chamber 29.

At 30 is shown a circulating coil or tube unit. This unit comprises end plates 31 and 32, in which are supported a plurality of circulating tubes, part of which are shown in Fig. 1 of the drawing. The tubes 33 communicate with the passage 26 at one end and the other end communicates with a chamber 34 in a header 35, the header having a central partition, as seen at 36. Thus, oil circulating through the tubes 33 into the chamber 34 will then circulate back through the tubes 37 into the lower portion of the chamber 29. The oil will then pass from the chamber 29 through the tubes 38 into the other chamber 39 of the header 35, the oil being discharged from the chamber 39 through the tubes 40 which open into the passage 28. From the foregoing, it will appear that a back and forth circulation amounting to what may be termed "four passes" is provided.

The header 35 includes an annular coupling flange 41 secured to the end plate 31 by bolts 42. These bolts also pass through an intermediate mounting ring 43 having gaskets 44 at both sides thereof. The ring 43 is coupled with another larger mounting ring 45 through the medium of a yieldable coupling 46 welded or otherwise secured to each of the rings 43, 45 and of U-shaped cross-sectional form. The coupling 46 provides an expansion coupling between the unit 30 or the header end 35 of said unit and the corresponding end of the casing 10, bolts 47 being employed to secure the mounting ring 45 to the flange 11 of the casing 10.

The chamber 21 opens into an annular chamber 48 in the header 22, as seen at 49.

The chamber 48 completely envelopes the annular reduced portion 50 of the header, within which the passages 26, 28 and 29 are arranged, as will clearly appear from a consideration of Fig. 3 of the drawing.

The reduced portion 50 has an end wall 51 which terminates short of the end wall 52 proper of the header 22 and this forms between the walls 51 and 52 a circulating chamber 53 which jackets the outer portion of the passages 26, 28 and 29, except where the tubular connectors 26a and 28a bridge the walls 51 and 52; thus, it may be said that the chambers 26, 28 and 29 are completely jacketed on outer surfaces thereof.

Centrally of the reduced portion 50 of the header 22 and centrally of the chamber 29 is a

conical tube 54, with which is coupled a circulating pipe 55 which extends centrally through the chamber 21 to a point short of the plate 31, as seen at 56. The tube 54 provides a further jacketing of the chamber 29 and this tube opens into the chamber 53.

Centrally of the header 22 and in alignment with the tube 54 is an opening 57 closed by a plate 58, in which is mounted a propeller shaft 59 driven by any suitable means for driving the propeller blades 60, disposed in the chamber 53 at the flared end of the conical tube 54. A suitable packing gland 61 is mounted on the plate 58 and around the shaft 59. With this construction, water or any other fluid heat conducting medium can be circulated through the casing 21 by forcing the fluid through the tube 55 and into the end of the chamber 21 at the discharge end 56 of said tube and this fluid will then circulate back and enter the chamber 53. In this way, the heating medium or transfer medium may be kept in constant circulation to provide efficient heating of the oil circulated through the tubes of the unit 30, as previously described.

The end plate 32 of the unit 30 is bolted or otherwise secured to the inner end of the reduced portion 50 of the header 22, as seen at 62 and suitable packings 63 are provided between the plate 32 and reduced portion 50 and a packing 64 is also provided between the flanges 12 and 23. In like manner, packings 65 are employed between the flange 41 and the mounting ring 45.

The header 22 has upper and lower passages 66 and 67, the latter forming an intake for water or other fluid to be introduced into the chamber 21; whereas the passage 66 may be used as an outlet in the event that a forced circulation is desired through the chamber 21 independent of the circulation previously described. However, when no circulation is provided, the passage 66 serves as means for placing gauge devices of other controls commonly employed in apparatus of the kind under consideration, particularly in the control of temperatures in the water or other medium arranged in the chamber 21, but these devices are not shown, as they form no part of the present invention.

Mounted in the lower portion of the header 22 is an inlet pipe 68 which passes through a gland 69 in the header and this pipe forms one end of a spiral coil 70 arranged in the chamber 21 around and outwardly of the tubes of the unit 30. The coil 70 extends substantially the full length of the chamber 21 and extending from the end coil 71 is a discharge tube 72 which is arranged within the coil 70 and the discharge end 73 thereof passes through a gland 74 at the top of the header casing 22.

A suitable heating medium, such as heated water, steam or the like, is introduced into the coil 70 through the pipe 68 to heat the transfer medium or fluid in the chamber 21 which in turn heats the oil in the circulating tube of the unit 30, as this oil is circulated back and forth through the unit in the manner previously described.

In this connection, it will be understood that, in referring to a preheater or heat exchanger, this is done to illustrate one adaptation and use of the invention. The apparatus may be used for any purpose and, in some instances, cooling agents will be used, rather than the heating agents and the various passages, tubes and chambers may be utilized for the circulation of different types and kinds of fluids, the important factor in the heat exchanger or preheater being that con-

tamination is avoided in the event of a break or leak in any of the circulating tubes of the unit 30 and this is particularly desirable when boiler water is circulated through the heating coil 70. It will be understood that the water or fluid in the chamber 21 and associated chambers will be simply a city water supply or water apart from the boiler water or steam circulated through the coil 70.

10 It will be understood that, by removing the bolts 24 and detaching the bolts 42 from the plate 41, the jacket including the header 35 can be removed, thus freely exposing the unit 30 as well as the coil 70 for cleaning and repair. As and when desired, the unit 30 may also then be removed by detaching the bolts 62 and this unit may be pulled through the coil 70 without removing this coil. On the other hand, couplings with the ends of the pipes or tubes 68 and 73 may be disconnected and the glands 69 and 74 loosened in the removal of the coil 70. All this can be done without disturbing connections with the pipes 25 and 27 and the pipes or other connections with the passages 66 and 67. Of course, if any connections have been made with the passages 13-16 inclusive, these connections will have to be uncoupled before the casing 10 can be removed, as above stated.

Having fully described our invention, what we claim as new and desire to secure by Letters Patent is:

1. In preheaters employing two headers and a casing joining and spacing said headers, a tube unit between the headers and in spaced relation to the casing, a spiral coil encircling the tubes of said tube unit within the chamber of said casing, means in one header only of the preheater for circulating fluid and similar mediums through the tubes of the tube unit, the other header joining the casing through a ring structure, said coil and the chamber of said casing, and means for detachably coupling the casing in conjunction with said ring structure from the first header without disturbing the tube unit and coil or any of the connections with said first header.

2. In preheaters employing two headers and a casing joining and spacing said headers, a tube unit between the headers and in spaced relation to the casing, a spiral coil encircling the tubes of said tube unit within the chamber of said casing, means in one header only of the preheater for circulating fluid and similar mediums through the tubes of the tube unit, the other header joining the casing through a ring structure, said coil and the chamber of said casing, means for detachably coupling the casing in conjunction with said ring structure from the first header without disturbing the tube unit and coil or any of the connections with said first header, and means for detachably coupling the tube unit with said first named header.

3. A preheater of the class described comprising an outer casing, headers detachable with respect to ends of the casing, one header being directly and detachably coupled with one end of the casing, a ring structure detachably coupling the other header with the other end of the casing, a circulating tube unit arranged in said casing in spaced relation to the walls thereof and detachably coupled with the first header and with the second header through said ring structure, the first named header having a plurality of passages in communication with the tubes of said unit, one of the passages forming the inlet 75 for a fluid to be heated, another passage forming

an outlet for said fluid, the other header having independent chambers placing the other ends of the tubes of said unit in communication, a spiral coil arranged in said casing and around the tubes of said unit, means in the first named header supporting inlets and outlets for said coil to provide circulation of a heating medium through the coil, means on the first named header for introducing a heat transfer medium into said casing around said tubes and coil, and means for detaching said casing, with the ring structure thereon, from the first named header without disturbing any of the fluid connections with the first named header and the tube unit and said coil.
